DESIGN FOR A NOVELTY PIN OR SIMILAR ARTICLE

Carol D. Prudden, Montclair, N. J.

Application September 20, 1940, Serial No. 95,240

Term of patent 7 years

To all whom it may concern:

Be it known that I, Carol D. Prudden, a citizen of the United States, residing in Montclair, county of Essex, State of New Jersey, have invented a new, original, and ornamental Design for a Novelty Pin or Similar Article, of which the following is a specification, reference being had to the accompanying drawing, forming a part thereof.

Fig. 1 is a front perspective view of a novelty pin showing my new design; and

Fig. 2 is a rear perspective view of the novelty pin illustrated in Fig. 1.

I claim:

The ornamental design for a novelty pin or similar article, substantially as shown.

CAROL D. PRUDDEN.
